CLAIM

The ornamental design for a speaker or similar article, as shown and described.

DESCRIPTION

FIG. 1 is a top front perspective view of a speaker or similar article showing our new design;

FIG. 2 is a front elevation thereof;

FIG. 3 is a top plan view thereof;

FIG. 4 is a side elevation thereof;

FIG. 5 is a rear elevation thereof;

FIG. 6 is a front elevation of a second modified embodiment of the speaker illustrated in FIG. 1;

FIG. 7 is a front elevation of a third modified embodiment of the speaker illustrated in FIG. 1;

FIG. 8 is a front elevation of a fourth modified embodiment of the speaker illustrated in FIG. 1;

FIG. 9 is a front elevation of a fifth modified embodiment of the speaker illustrated in FIG. 1; and

FIG. 10 is a front elevation of a sixth modified embodiment of the speaker illustrated in FIG. 1.
